BLOOD LANCET

George W. Jacoby, Jr., Wooster, Ohio

Application February 14, 1951, Serial No. 210,874

7 Claims. (Cl. 128—314)

1

This invention relates to surgical instruments, and more specifically, to lancets for piercing human tissue to obtain blood samples. In the past, blood samples have been obtained by piercing a finger tip with a lance or stylet operated by a spring release mechanism. The stylet would thereupon thrust the tissue toward the bone and often times would strike the bone, thus causing pain to the patient.

It is an object of this invention to provide a lancet which will pierce the tissue of a finger or earlobe and cause a minimum of pain and distress to the patient.

Another object of this invention is to provide a lancet which has parts for elevating and holding tissue in a rigid manner previous to and during the puncturing operation.

A still further object of this invention is to provide a lancet which pierces the tissue to a uniform depth which is adjustable and is controlled by parts associated with the lancet-carrying means.

Another important object of this invention is to provide a lancet and frame structure which may be easily dis-assembled and is also arranged for ease of cleaning and sterilization.

Another object of this invention is to provide a lancet structure which has the cutting element removable for replacement upon deterioration with use.

Other objects and advantages, more or less ancillary to the foregoing, and the manner in which all the various objects are realized will appear in the following description, which, considered in connection with the accompanying drawings, sets forth the preferred embodiment of the invention.

In the drawings:

Fig. 1 is a perspective assembly view of the lancet;

Fig. 2 is a side view of the lancet in tissue-holding and piercing position; and

Fig. 3 is a perspective view showing the stylet moved from the operating position to the cleaning position.

Referring first to Fig. 1, the preferred embodiment of my invention has a bifurcated frame, generally designated by the numeral 10, having a handle 12 and a pair of legs 14 and 16. The legs 14 and 16 are formed so that they are resiliently carried by the handle 12 and may be moved toward each other with ordinary finger pressure. A pair of jaws 18 and 20 are formed on the ends of each of the legs 14 and 16 respectively, opposite to the handle 12 by lateral recesses 22 in opposed relationship on the inner walls of legs 14 and 16.

A stylet 24, which is in the form of a flat-bladed, double-edged, pointed knife, is mounted on a resilient arm 26 for movement toward and away from the jaw 18. The jaw 18 has a stylet

2

receiving notch 28 formed therein. A second notch 30 is formed in jaw 20 in register with notch 28 so that the stylet 24 may pass through the notch 28 and be received by the notch 30. The notch 30 receives the stylet 24 when the jaws 18 and 20 are brought together, thus eliminating damage and dulling which would result from the stylet 24 interfering with the jaw 20 in the absence of such a provision. When the instrument is in use, the stylet would not extend to the notch 30 unless the tissue held between the jaws 18 and 20 were extremely thin.

A rectangular channel is disposed in the outside wall of leg 14 for receiving arm 26 and holding the arm 26 against rotational movement when the stylet 24 is in the notch 28. The arm 26 is held in the channel 32 by the thumb screw 34 which passes through the arm 26 and is threadably engaged with the leg 14. A transverse groove 36, in line with the thumb screw 34 and normal to the medial axis of the channel 32, is complementary in shape to the arm 26 and is utilized for holding said arm in an alternate position indicated in Fig. 3.

The extent of travel of the arm 26 and stylet 24 is limited by the adjusting screw 38. The rotation of the screw 38 moves the same inwardly and outwardly as required to obtain the desired penetration of the stylet 24 past the inner surface of jaw 18.

The lancet is ordinarily held in the hand as indicated in Fig. 2. The thumb engages leg 16 and the forefinger the leg 14. The third finger is utilized to press the arm 26 downwardly to force the stylet through the notch 28.

The use of the instrument is indicated in Fig. 2 wherein the lancet is held in the hand like a pencil and is used to puncture the tissue of the finger of a patient to obtain a blood sample. The lancet is moved into tissue-engaging position with the jaw separated, as indicated in Fig. 1, whereupon pressure is exerted on the legs 14 and 16 by the thumb and forefinger of the hand, thus picking the tissue up and holding it rigidly in preparation for the cutting or puncturing operation. With the tissue picked up and held by the jaws 18 and 20, absolute control over the part to be punctured is maintained and the dull pressure in pinching the skin produces a dull pain which is not objectionable but exceeds the pain produced by the sharp lancet. The patient, therefore, is unaware when the penetration of the lancet takes place.

With the tissue held securely in the jaws, the cutting edge of the stylet is moved by the third finger of the operator's hand until the arm engages the screw 38. In this manner, the fold of the tissue is pierced through the side thereof at right angles and in a direction approximately parallel to the bone. The position of

the adjusting screw 38, therefore, will determine the depth of penetration obtained by the operation of the stylet. By piercing the fold of tissue transversely, it is impossible to penetrate to the bone, thereby eliminating increased pain to the patient. One of the disadvantages of the spring-release type stylet is, therefore, eliminated.

After the lancet has been used, the stylet may be moved into position for cleaning by releasing the thumb screw 34 and rotating the arm 26 to a position normal to the leg 14 whereupon the stylet 24 is free of the jaws 18 and 20. Further, the jaws may be cleaned with facility since the sharp stylet has been removed therefrom and only rounded edges remain. It may be noted that all parts of the assembly will be unaffected by heat and, therefore, it is well adapted to high temperature sterilization as ordinarily carried forward in laboratories and hospitals.

Removal of thumb screw 34 allows the rapid replacement of arm 26 and stylet 24 when required by the stylet becoming dull. The frame 10 is made especially sturdy for long life while the stylet and arm are designed to be expandable and replaceable at a minimum cost after a period of use.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

What is claimed is:

1. A surgical instrument for piercing the skin comprising a frame having a pair of jaws shiftably mounted thereon, a resilient arm having one end affixed to said frame, a knife mounted on the other end of said arm, and a notch in one of the jaws adjacent said arm, said knife being movable through said notch whereby the skin retained by the said jaws is punctured when the knife is moved toward the jaws.

2. A surgical instrument for piercing the skin comprising a frame having a pair of jaws resiliently mounted thereon, a resilient arm having one end affixed to said frame, a knife mounted on the other end of said arm, and a notch in one of the jaws adjacent said arm, said knife being movable through said notch whereby the skin retained by the said jaws is punctured when the knife is moved into the notch.

3. A surgical instrument for piercing the skin comprising a frame having a pair of jaws shiftably mounted thereon, knife means carried for

movement by the frame, and a notch in one of the jaws, said knife being movable through said notch whereby the skin retained by the said jaws is punctured when the knife is moved through said notch.

4. A surgical instrument for piercing the skin comprising a frame having a pair of jaws shiftably mounted thereon, a resilient arm having one end affixed to said frame, knife means shiftably carried by the other end of said arm, and a notch in the jaw adjacent said arm, said knife being movable through said notch whereby the skin retained by the said jaws is punctured when said knife is moved through said notch.

5. A surgical instrument for piercing the skin comprising a frame having a pair of jaws shiftably mounted thereon, a resilient arm having one end affixed to said frame, the opposite end of said arm being spaced from one of said jaws, knife means shiftably carried by the movable end of said arm, and a notch in the jaw adjacent said arm for receiving said knife whereby the skin retained by the said jaws is punctured when said knife is moved through said notch.

6. A surgical instrument for piercing the skin comprising a frame having a pair of jaws shiftably mounted thereon, a resilient arm having one end affixed to said frame, knife means carried by the other end of said arm movable into skin-engaging position when said skin is retained in said jaws, and screw means on said frame for limiting the travel of said knife toward the jaws.

7. A surgical instrument for piercing the skin comprising a frame having a pair of jaws shiftably mounted thereon, a resilient arm having one end affixed to said frame, knife means carried by the other end of said arm movable into skin-engaging position when said skin is retained in said jaws, and an adjusting screw on said frame for limiting the movement of said knife toward the jaws.
